METHOD OF MAKING ARTICLES FROM CASEIN

Application filed May 2, 1927. Serial No. 188,257.

This invention relates to an improved method of making articles from casein, its underlying object being to produce the articles practically in a single operation which leaves them smooth and without a die-mark of any kind, and further effects a material saving in labor and time.

In the accompanying drawings, the method is shown as applied to the manufacture of buttons or similar articles. Figs. 1 and 2 show a plan and sectional elevation, respectively, of a female die used in carrying the invention into effect, while Figs. 3 and 4 illustrate the complementary male die; 15 and Figs. 5 to 7 illustrate the successive steps in forming the articles and ejecting them from the dies.

The female die has stationary forms 8 inserted in the die plate 9 and secured to a bottom plate 10 by screws 11. The male die has slidable forms 12 provided with shoulders 13. These forms are inserted in a die plate 14 and are held in place by the recessed bottom plate 15, the depth of the recess in the plate 15 being greater than the height of the shoulders 13 by the amount of movement desired for the forms 12.

The casein, as it comes from an extruding machine, is in the form of rods or bars 30 which are immediately cut up into slugs 16. Each slug 16 is long enough to extend across one row of the forms 8 in the female die. The male die is then placed in registration with the female die by means of the guide pins 17 carried by the female die and the holes 18 formed in the male die, as shown in Fig. 5. It is not, however, essential that the buttons be made of slugs of the kind just described, for they may be made from 40 a sheet of casein covering all of the forms 8.

When the male and female dies have been brought together with the plastic material between them, they are placed in a suitable press having platens which may be heated 45 by steam and cooled by water circulation. Such presses are used in the manufacture of casein by other methods, though in a different way.

As soon as the dies have been placed in 50 the press, heavy pressure is applied to the

same, the surplus material being driven out into the space 19 between the die plates 9 and 14 leaving only a very thin film of material in the spaces between the individual forms, these spaces being exaggerated in the drawings, in the interest of clearness. A few seconds after the casein has been pressed into the form shown in Fig. 6, steam is turned on the platens of the press and the heat therefrom communicated to the buttons now formed and still under pressure. After the heat has been thus applied for a few moments, the steam is turned off and cold water is circulated through the platens of the press, which of course cools 60 the dies contacting therewith, and they in turn cool the buttons still under pressure, the whole operation—in the case of buttons—being completed in a few minutes. The advantageous results obtained by this 70 sequence of steps may be noted at this point. By molding the casein while it is cool and then heating it while still under pressure, the customary polishing and finishing operations on the molded articles are rendered 75 unnecessary, as the result of this sequence of steps is the production of articles, the surface of which is as smooth or polished as the surfaces of the molding forms used. This is due to the internal pressure developed in the casein by operation of its high coefficient of expansion, the material being expanded by the heating step while still 80 under pressure in the molds to provide the smooth surface. By the final step of cooling the molded articles while they are still under pressure, the material contracts sufficiently to free the material from the molding forms and without warping either during 85 the cooling operation or thereafter. 90

When the buttons have been formed, as in Fig. 6, they are connected only by a very thin film of casein, the space between the die plates 9 and 14 being exaggerated in the figure. This film is only a few thousandths 95 of an inch thick, and it occurs at the junction line of the lower surface and the perimeter of each button, so that the only die-mark there is coincident with a corner of the button where it is not dis- 100

tinguishable from the corner itself when the buttons are finally broken away from this thin film. The formed casein having been embedded in the holes in the plate 14 by the recession of the forms 12, as shown in Fig. 6, the ejection of the formed buttons after cooling is accomplished by removing the female die and pushing the forms 12 of the male die down by means of an ejector 20, having pins 21, registering with the holes 22 in the recessed plate 15, the male die being supported by a suitable frame or box 23 during this operation, as shown in Fig. 7. When the shoulders 13 of the forms 12 reach the plate 14, the formed buttons are freed from the male die and drop into the box 23.

In performing the operations illustrated in Figs. 5, 6 and 7, the actual position of the dies is of course immaterial as long as their relative position remains the same. These operations, therefore, may be performed equally well in the positions obtained by inverting Figs. 5, 6 and 7, respectively.

25 The buttons or other articles made by this method require no further finishing operation unless it is desired to cure or harden them, which may be done in any of the ways already known, as by submerging them in formaldehyde for a long period without pressure, or for a much shorter period under pressure.

What is claimed is:

1. The method of making articles from casein, which consists in first subjecting cool uncommunited extruded casein to pressure to give it the form of the desired articles and while still under said pressure heating and then cooling it.

40 2. The method of making articles from casein, which consists in first subjecting cool uncommunited extruded casein to pressure to give it the form of the desired articles and while still under said pressure heating and then cooling it, and subsequently curing the articles.

3. The method of making articles from casein, which consists in first subjecting cool uncommunited extruded casein to pressure to give it the form of a plurality of the desired articles and while still under said pressure heating and then cooling it, and subsequently separating the articles.

45 4. The method of making articles from casein, which consists in first placing cool uncommunited extruded casein in complementary dies having a parting line coincident with the junction line of different surfaces of the articles, then subjecting the casein so placed to pressure to give it the form of the molds and articles and while still under said pressure heating and then cooling it.

5. The method of making articles from casein, which consists in first subjecting a

cool uncommunited mass of casein to pressure to give it the form of the desired articles and while still under said pressure heating and then cooling it.

6. The method of making articles from casein, which consists in first placing a cool uncommunited mass of casein in complementary dies having a parting line substantially co-incident with the junction line of different surfaces of the articles, then subjecting the casein so placed to pressure to give it the form of the molds and articles and while still under said pressure heating and then cooling it.

In testimony whereof, I have signed my name to this specification.
